INFLATABLE FIGURE TOY

George Azov and Solomon Tkatch,
San Francisco, Calif.

Application March 19, 1949, Serial No. 1,495

Term of patent 3½ years

(Cl. D34—15)

To all whom it may concern:

Be it known that we, George Azov and Solomon Tkatch, both citizens of no country, residing at 70 Barcelona Street, city and county of San Francisco, State of California, have invented a new, original, and ornamental Design for an Inflatable Figure Toy, of which the following is a specification, reference being had to the accompanying drawing, forming part thereof in which

Fig. 1 is a side view of our inflatable figure toy in normal contracted position, showing our design.

Fig. 2 is a side view of our toy in partially expanded position.

Fig. 3 is a side view of our toy in fully expanded position; and

Fig. 4 is a rear view of our toy as shown in Fig. 3.

We claim:

The ornamental design for an inflatable figure toy, as shown.

GEORGE AZOV.
SOLOMON TKATCH.
